UNITED STATES PATENT OFFICE.

PATRICK J. O'BRIEN, OF ELYRIA, OHIO.

TOOL-DIRECTING MACHINE.

1,032,933.

Specification of Letters Patent. Patented July 16, 1912.

Application filed December 10, 1910. Serial No. 586,686.

To all whom it may concern:

Be it known that I, PATRICK J. O'BRIEN, a subject of the King of Great Britain, residing at Elyria, in the county of Lorain 5 and State of Ohio, have invented certain new and useful Improvements in Tool-Directing Machines; and I do hereby declare the following to be a full, clear, and exact description of my invention, such as will enable others skilled in the art to which it appertains to make and use the same.

My invention relates to devices for accurately directing tools, such for example as drills, reamers and the like, though I do not 15 wish to be limited to any particular class of tool. In some classes of work it is desired to drill holes or do other operations upon work in very accurate alinement. The ordinary machines are not accurate enough to do this 20 work as desired.

My invention aims to produce a device which provides an arrangement of apparatus for accurately directing the tools to the desired point on the work.

I also provide a device which is accurate, which admits of adjustments, which is 25 cheaply and easily constructed and which may be handled by people who are capable of handling such machines as I have described.

I also provide means for keeping the adjustments proper and for taking up wear and change of dimensions due to atmospheric conditions.

My invention and objects thereof, will be best understood by reference to the detailed description when taken in connection with the drawing. I have made these objects though I do not wish it understood that 35 these are the only ones which I have in view, as I desire to realize all the ends which my means are capable of.

The scope of the invention itself, is pointed out in the appended claims.

Figure 1 is a plan view of my invention. Fig. 2 is a front elevation of the invention. Fig. 3 is a plan view of the bottom showing the means for rotating the support. Fig. 4 is a vertical cross section taken through the 45 center of Fig. 2. Fig. 5 is a detailed view showing the tool directing device itself with the work being set therefor. Fig. 6 is a similar view showing a drill directed by this device. Fig. 7 is a similar view showing a 50 reamer. Figs. 8 and 9 show specimens of work which have been operated upon by

tools directed by my device and which will serve to show the capabilities of my machine.

Referring now to the drawings, the frame 60 is shown at 1. This frame is supported upon legs 2. Pillars 3 are erected from the frame. The machine is placed upon a drill table in such a way that it is supported by the legs of the machine, which rests upon the table. 65 The bottom of the frame is perforated at 4. Upon one side of the frame I show a pointer 5. A worm 6 girded upon a worm shaft 7 is mounted in hangers 8, which are fastened by screws to the bottom of the frame. A 70 support 10 is mounted in the frame. A projection 11 on the bottom of this support projects through the opening 4 in the bottom of the frame. A worm gear 12 is keyed on this projection by a key 13. The lower end 75 of the projection is threaded and a lock nut 14 screwed thereon to hold the worm gear in position. The worm gear meshes with the worm 6. A scale 15 is shown upon one edge of the support 10 and cooperates with 80 the pointer 5. It will be seen that the support is rotated in the frame by the worm 6, the amount of rotation being accurately determined from the co-operating scale 15 and the pointer 5. Clamps 16 are shown in the frame which lap over the edge of the support assisting to hold the same in position. 85 A turret 17 is shown in the center of this support. This turret is cut away at 18 and a threaded shaft 19 having each end journaled in the edge of the turret is mounted in this opening. A micrometer disk 20 is fastened upon the end of the shaft 19 so that the two move together. The disk is held upon the shaft by a lock nut 21. A pointer 90 95 mounted upon the support cooperates with the disk to enable the operator to accurately determine the distance through which the disk is rotated. The shaft 19 is enlarged at one end, as shown at 23. Two lock nuts 24 are shown upon the enlarged end of the shaft and normally abut against the inside edge of the turret, holding the shaft accurately in the proper position. These nuts turn with the shaft. The turret 100 is beveled as shown at 25. A base member 26 oppositely beveled at 27 is mounted upon the support. The base is adapted to slide upon the support, engaging the beveled portions which act as guiding ways. At 30 I 105 show a key which fits between the beveled surfaces of these two parts and which en-

ables me to adjust the parts so as to take up losses due to general wear, temperature, etc. A lug 31 is mounted upon the bottom of the base and projects therefrom into the opening 18 in the support. This lug is pierced and a threaded bushing 32' fastened therein. This bushing is threaded to engage the threads of the shaft 19.

32 is an adjusting device for taking up 10 the losses or gains due to wear, temperature, etc.

The bottom of the base is hollowed as shown at 33, to permit the base to slide forward over the micrometer disk 20. When 15 the micrometer disk is rotated, the threaded shaft will turn in the lug 31, giving the base a rectilinear motion backward and forward along the support. T-slots 34 are cut in the top of the base. Clamps 35 are mounted 20 upon the top of the base. Bolts 36 pass through the lower limbs 37 of these clamps into the slots in the base, the heads 38 of the bolts fitting in the slots. The clamps are drawn to the base by nuts 39 on the bolts. 25 It will thus be seen that the clamps have a movement along the support in a direction perpendicular to the plane of the paper in Fig. 2. The upright arms 40 of these clamps are pierced and bolts 41 mounted 30 therein. The heads 42 of these bolts serve as clamping jaws. The center of the upright limbs is cut away, as shown at 43 and nut 44 threaded on the bolts, mounted in these openings. By turning the nut 44, I 35 realize a finer adjustment of the jaw 42. These jaws coöperate with a stationary jaw 45 on the opposite side of the base. At 46 I show a facing fastened by a screw 47 to the stationary jaw. The work or the material upon which work is to be done, which for the sake of convenience I here call the work, is clamped between these jaws. It 40 will be readily seen, without describing the operation that this work may be rotated 45 about an axis through the center of the projection 11 and may be moved rectilinearly in a direction perpendicular to the plane of the paper in Fig. 2.

A bridge 50 is hinged, as shown at 51 upon two of the standards 3. As will be readily seen, this bridge can be rotated about a horizontal axis and is lifted up to allow the work to be placed upon the base. The opposite standards are cut away to allow 55 the bridge to fit closely therein when placed in normal position. Clamps 52 are mounted upon these opposite pillars to grip the bridge and hold it in position. Winged nuts 54 are employed to tighten the clamps 60 52. A substantially rectangular opening 55 is cut in the central part of the bridge. Each side 56 of this rectangular opening serves as a guiding way for a device which will be described hereinafter. Beveled slots 65 57 are cut in each of the inner edges of the

guiding ways. A threaded shaft 58 is journaled in this opening, parallel to the guiding ways, each end of the shaft being journaled at 59 in one of the ends of the bridge. A micrometer disk 60, is mounted upon one end of this shaft and coöperates with a pointer 61 on the bridge. Lock nuts 62 hold the shaft in position. The arrangement of apparatus in connection with this shaft is identical with that described in connection with the shaft 19 and will not be repeated in detail.

At 63 I show a slide which carries beveled projections 64 on each side thereof. These projections fit into beveled slots in the guiding-ways. The slide is pierced and threads cut in the opening which engage with the shaft 58 so that the slide is moved along the bridge when the micrometer disk is rotated. The edges of the slide lap over the top of the bridge, as shown at 70. Pointers 71 are mounted upon the edge of the slide, the front one coöperating with a scale 72 upon one side of the bridge. A key 74 is employed between the slide and the bridge to take up 80 adjustments due to wear, temperature, etc. A vertical hole is bored at 76 in the slide. This hole is partly threaded and a threaded bushing 77 screwed into the hole. In the other part of the hole, a second bushing 78 is 90 mounted. The bushing 77 carries a knurled portion 79. This bushing 77 is removably fastened in the slide and may be taken out and other bushings substituted. The bushing 78 serves to accurately align the removable bushing. The bushing 79 operates to accurately direct the tool. I have shown a bushing for this purpose, because this is the best means for directing a tool which occurs to me. I intend to employ any device which 100 will serve this purpose and may use the bare opening in the slide without departing from the spirit of my invention.

90 is a lock nut for holding the slide and is similar to that shown at 32. A threaded 110 shaft 91 is rigidly mounted upon the slide. A key 92 is mounted in the beveled slot in one of the guiding ways. An arm 93 projects from this key. The key 92 abuts against the slide and moves therewith. 115 Both the slide and the key are tapered to permit the key to glide up on the slide along this tapered portion. Nuts 100 are mounted on the threaded shaft on opposite sides of the arm 93. Final adjustments may be 120 given the slide by employing this device. The two engaging wedge surfaces of the key and slide glide over each other when the nuts 100 are adjusted camming the slide in one direction or another according to the direction of movement of the nuts and moving said slide perpendicular to its direction 125 along the threaded shaft 58.

The operation of my device will be readily understood from the description of the ap- 130

paratus. I furnish adjustments in two directions to the work and the final adjustment is made independent of the work. This enables me to make the final adjustment without danger of disturbing the other two.

5 In Fig. 5 the slide is shown at 63, the bushing at 77 and a steel plug 101 penetrating the bushing for the purpose of placing the work 102.

10 In Fig. 6 I show a similar arrangement, except a drill 103 is employed to penetrate the bushing and operate upon the work 102.

In Fig. 7 I show a reamer 104.

15 Figs. 8 and 9 show work 102" and 102"" clamped between the jaws of the base. These pieces of work have been operated upon and each shows a plurality of holes. Those in Fig. 8 are made in positions which 20 have been reached by the devices which give rectilinear motion to the work and the slide. Those in Fig. 9 have been reached by the operation of all three devices.

25 While I have shown this particular form and described these particular purposes, it will be apparent to those skilled in the art that numerous and extensive departures from the details of the apparatus here shown may be made without departing from 30 the spirit of the invention as defined in the appended claims, the same being shown herein solely for the purpose of clearly illustrating one specific embodiment of my invention.

35 I claim:

1. In a device of the class described, the combination of a frame, a base supported from said frame, micrometer governed means for moving said base relative to said frame, mechanism for fastening the work to said base, guiding ways supported from and hinged to their support, a slide mounted to move in said ways, a hollow bushing carried by said slide and adapted to direct a tool 40 to the work and micrometer governed means for moving said slide in said ways.

2. In a device of the class described, the combination of a frame, a base supported from said frame adapted to support the work, a pair of ways hinged to said frame, a slide mounted in said ways, said slide having a threaded opening therein, a tool directing device mounted in said slide, a threaded shaft mounted in said ways adapted 50 to engage the threaded opening in the slide and means to rotate said shaft to move the slide along the ways.

3. In a device of the class described, the combination of a frame, a base supported 55 from said frame adapted to support the work, guiding means supported from said frame, a threaded slide adapted to move in said guiding means, a tool directing device carried by said slide, a threaded shaft engaging the threaded slide and means to ro-

tate said shaft to move said slide relative to said base.

4. In a device of the class described, the combination of a frame, a base supported from said frame adapted to support the work, guiding ways hinged to said frame, a slide mounted to move in said guiding ways, a tool directing device carried by said slide and means to move said slide in said guiding ways.

75 5. In a device of the class described, the combination of a frame, a movable base adjustably secured to said frame adapted to support the work, guiding ways hinged to said frame, a slide mounted in said ways, a tool directing device carried by said slide, and means including a threaded shaft for moving said slide along said ways.

80 6. In a device of the class described, the combination of a frame, a base supported from said frame, micrometer governed means for moving said base relative to said frame, mechanism for fastening the work to said base, guiding ways supported from and hinged to their support, a slide mounted to move in said ways, a tool directing device carried by said slide and adapted to direct a tool to said work and micrometer governed means for moving said slide in said ways.

95 7. In a device of the class described, the combination of a frame, a support mounted in said frame, means to rotate said support in said frame, a base carried by said support, micrometer governed means for moving said base relative to said support, said base adapted to support the work, guiding ways supported by said frame and hinged thereto, a slide mounted to move in said ways, said slide normally mounted over the position in 100 which the work is supported, means to move said slide relative to the work and a tool directing device carried by said slide.

105 8. In a device of the class described, the combination of a frame, a base supported by said frame adapted to support the work, guiding ways supported from said frame having longitudinal slots cut therein, a beveled slide mounted to move in the slots in said guiding ways, a tool directing device 110 carried by said slide and means to move said guide in said ways.

115 9. In a device of the class described, the combination of a frame, a base mounted in said frame, means to move said base relative to said frame, mechanism for attaching the work to said base, guiding ways hinged to said frame, said ways being slotted and being adapted to be swung upon their hinges to permit the positioning of the work on 120 the base, a beveled slide mounted to move in the slots in said ways, a tool directing device carried by said slide and means to move said slide in said ways relative to said base.

10. In a device of the class described, the combination of a frame, a base supported from said frame, adapted to support the work, guiding means supported from said frame, a threaded slide adapted to move in said guiding ways, a removable hollow bushing carried by said slide for directing a tool, a threaded shaft engaging the threaded slide, and means to rotate said shaft to move said slide relative to said base.
11. In a device of the class described, the combination of a frame, a base supported from said frame adapted to support the work, guiding ways hinged to said frame, a slide mounted to move in said guiding ways, a hollow bushing for directing a tool, said bushing being carried by said slide, and means to move said slide in said guiding ways.
20. 12. In a device of the class described, the combination of a frame, guiding ways hinged to said frame, a base mounted in said frame adapted to support the work, means

to move said base rectilinearly, a hollow bushing removably associated with said parts, adapted to direct a drill or similar tool and supporting means for said bushing mounted independently of the tool, one of said supporting means being movable relative to the other to position the work to the tool.

13. In a device of the class described, the combination of a frame, a base supported by said frame adapted to support the work, guiding ways supported from said frame having longitudinal slots cut therein, a beveled slide mounted to move in the slots in said guiding ways, a hollow bushing adapted to direct a tool carried by said slide and means to move said slide in said ways.

In testimony whereof, I affix my signature in the presence of two witnesses.

P. J. O'BRIEN.
